(57) **CLAIM**

The ornamental design for a diaper for newborn infants having internal sling with opening for umbilicus, as shown and described herein.

DESCRIPTION

FIG. 1 is a perspective view of a diaper for newborn infants having internal sling with opening for umbilicus, showing my new design;

FIG. 2 is a front view thereof;

FIG. 3 is a rear view thereof;

FIG. 4 is a side view thereof, the opposite side view being identical;

FIG. 5 is a top view thereof; and,

FIG. 6 is a bottom view thereof.
